CARBURETOR

Walter H. Weber, Detroit, Mich., assignor to Detroit Lubricator Company, Detroit, Mich., a corporation of Michigan

Application December 31, 1929, Serial No. 417,609

37 Claims. (Cl. 261—34)

My invention relates to new and useful improvements in carburetors for supplying a combustible charge to the cylinder or cylinders of an internal combustion engine.

5 In such carburetors it has been found that a combustible charge having the proper ratio of liquid fuel to air, to be economical for normal operating conditions, does not provide the requisite ratio of liquid fuel to air for quick starting, the "warming-up" period, rapid acceleration, and high power demands of the engine, particularly when employed to drive a motor vehicle.

An object of my invention is, therefore, to 15 provide a carburetor which will operate efficiently to supply a proper combustible charge to the engine for all periods and conditions of its operation.

20 Other and further objects and advantages of a carburetor embodying my invention will appear hereinafter in the detailed description of structure and operation thereof.

The invention consists in the improved construction and combination of parts and their 25 aggroupment in operative relation, to be more fully described hereinafter, and the novelty of which will be particularly pointed out and distinctly claimed.

In the accompanying drawings, to be taken 30 as part of this specification, I have fully and clearly illustrated a preferred embodiment of my invention and certain modifications thereof, in which drawings—

Figure 1 is a top plan view, with certain parts 35 broken away, of a carburetor of my invention;

Fig. 2 is a view of the carburetor in front elevation, partially in vertical central section and having parts broken away;

Fig. 3 is a view in end elevation looking from 40 the left toward the right of Fig. 1;

Fig. 4 is a view in end elevation, partially in section on line 4—4 of Fig. 1, and showing in dotted lines the full open position of certain vane members;

Fig. 5 is a view in end elevation and in section on the line 5—5 of Fig. 2;

Figs. 6, 7 and 8 are detail sectional views on the line x—x of Fig. 2, showing the relative positions of certain ports and passageways during 50 operation;

Fig. 9 is a detail view in vertical central section of a modification of my invention, and

Figs. 10, 11 and 12 are horizontal group, detail views on the lines 10—10, 11—11 and 12—12, respectively, of Fig. 9, each horizontal row or group

showing from left to right the relative positions of certain ports and passages during operation of the modification of Fig. 9.

Referring to the drawings by characters of reference, 1 designates, generally, a carburetor, preferably of metal, and comprising a body member of hollow construction having air and fuel inlets and including a base member 2 and a throttle body member 3. The member 2 has a bottom wall 4 from which rise substantially parallel side walls 5, 6, respectively, and end walls 7, 8, respectively, which join the walls 5, 6. Intermediate the walls 7, 8 is a partition or wall member 9 which extends transversely between and joins the walls 5, 6. The substantially rectangular space defined by walls 5, 6, 8 and 9 comprises an air inlet chamber 10 which is supplied with air, preferably atmospheric, by an air inlet passage or conduit 11 which opens through the end wall 8 and which is preferably substantially cylindrical. The entrance to passage 11 is preferably guarded by means of a deflector plate or baffle 12 rigidly supported in overlying spaced relation to the mouth of passage 11 by a bracket member 13 fixed to member 2 by screws or the like 14. The end wall 7 is preferably curved horizontally and defines with walls 5, 6, 9 and bottom wall 4 a float chamber or fuel reservoir 15. Within chamber 15 is a vertical bracket 16 (Figs. 2 and 5) integral with and extending outward from wall 9, upward from wall 4, and terminating below the top of chamber 15. Between bracket 16 and side wall 5, is an internally threaded vertical sleeve 17, the bore of which opens through an aperture 18 in wall 4. Depending from the under side of bottom wall 4 and concentric with aperture 18, is a flange 19, preferably circular. Threaded into sleeve 17 through aperture 18, is a stud 20 having in its upper end an axial bore 21 opening into a transverse passage 22 through said stud and within flange 19. On the stud 20 is a cup-like member 23 having an aperture 24 in its bottom wall through which the stud 20 projects. Between the rim of member 23 and the under face of flange 19 is held the periphery of a strainer element 25, preferably a screen of fine wire mesh, which surrounds the stud 20. The element 25 and member 23 are clamped tightly in position against flange 19 by a cap nut 26 threaded on the free end of stud 20. The member 23 has a fuel inlet 27 through the bore of an externally threaded nipple 28 for connection of the carburetor to a source of fuel supply. Threaded into the top of sleeve 17 is a valve guide and seat member 29 having a vertical bore 30 therethrough 110

which is of reduced diameter near its lower end to provide a valve seat 31, above which is a transverse passage 32 through member 29 for admission of fuel to the reservoir 15. In the guideway 5 or bore 30 is a valve member 33, preferably of the needle type, which cooperates with seat 31, said member having a stem 34, preferably polygonal, which extends above sleeve 17 and has a collar member 35 secured thereon and engaged by the arms of a yoke 36 carried by the end of a float lever 37 which is pivotally supported on a pin 38 extending between and secured in apertures in bracket 16 and wall 5 (see Figs. 1 and 2). Secured rigidly on the free end of lever 37 is a float 39 for controlling the valve 33 and the admission of fuel to the reservoir 15. A cover plate or member 40 overlies and closes the reservoir, and is preferably secured to the member 2 by screws 41, 41^a. In order to maintain air at atmospheric pressure over the liquid in the reservoir, the cover member 40 is provided with an air inlet 40^a formed by indenting the under side of said cover member to form a passage over the edge of the wall 9.

I will now describe means for admitting and controlling the main supply of air and fuel to form the main charge or mixture to be supplied by the carburetor: Extending between walls 8, 9 and adjacent and substantially parallel to front wall 5, is a shaft 42 having its opposite ends supported in bearing recesses 43 in the top faces of walls 8, 9. Adjacent and substantially parallel to the rear wall 6 is a shaft 44 which extends between and has its opposite ends supported in bearing recesses 45 in the top faces of walls 8, 9 (Figs. 1 and 2). Journalled on shafts 42, 44 are the hub portions 46, 47, respectively, of vane or air flow control members 48, 49, which are substantially rectangular in plan outline. The members 48, 49 have head portions 50, 51 which are substantially rectangular and which meet substantially in the vertical plane through the longitudinal center line of passage 11. Joining the head portions and the hub portions of members 48, 49 are plate portions 52, 53, respectively, the under surfaces of which are inclined upwardly from the horizontal at substantially forty-five degrees, when members 48, 49 are in closed position (Fig. 4). Seated on the top faces of walls 5, 6, 8 and 9 is a plate member 54 which overlies and closes the recesses 43, 45 and serves as a top bearing face for the ends of the shafts 42, 44 and to retain the shafts in position. Through the member 54 is a substantially rectangular opening 55 which from front to rear is substantially equal to the distance between walls 5 and 6 and from side to side is substantially equal to but slightly greater than the width of members 48, 49, so that the members 48, 49 project movably therethrough. From member 54 at the sides of the opening 55 and adjacent walls 8, 9, rise substantially parallel guide plate members 56, 57, respectively, which are spaced apart a distance substantially equal to but slightly greater than the width of vanes 48, 49, and which terminate at a height substantially equal to the length of said vanes when the latter are in full open position, as shown in dotted lines in Fig. 4. On the inside faces of the members 56, 57 are deflector members 58, 59, respectively, which lie under the vane members 48, 49 (see Figs. 2 and 4), and which are inclined upwardly toward each other from the bottom edge of the opening 55, the inclination of member 58 being preferably about twenty degrees and of member 59 about

ten degrees. The side edges of each of members 58, 59 are inclined upwardly toward each other substantially parallel to the under faces of the vane members 48, 49 when the members 48, 49 are in closed position. In the meeting faces of the head portions 50, 51 of the vanes, midway between members 56, 57 are vertical, semi-cylindrical, oppositely positioned recesses 60, 61, which cooperate when portions 50, 51 are in engagement, to provide a cylindrical aperture 62 therethrough.

In the air inlet chamber 10 and substantially concentric with aperture 62, is a sleeve member 63 which rises vertically from the bottom wall 4 substantially to the height of the chamber 10 (see Fig. 2). Vertically through the sleeve member 63, wall 4 and a boss 64 depending from wall 4, is a cylindrical bore 65 which is concentric with aperture 62, substantially the top third of said bore being of reduced diameter, as at 66, to serve as a guideway and to provide a downward facing annular shoulder 67 forming the top wall of a dash-pot chamber 68. Extending between wall 9 and sleeve member 63 is a horizontal boss 69, and through the wall 9, boss 69, and the wall of sleeve member 63, is a fuel supply conduit 70 which opens at one end into the reservoir 15 and at its other end into the bore 65 beneath the dash-pot chamber 68. In the chamber 68 is a piston 71 of slightly less diameter than the diameter of chamber 68 to provide for a flow clearance around the piston. Rigid with said piston and extending upward centrally therefrom, is a rod 72 which extends above sleeve member 63, as at 73, and is of a diameter substantially equal to the diameter of the sleeve guideway portion 110 66, but which has a free sliding fit therein. Longitudinally through the piston 71 and rod 72 is a fuel feed passageway 74. On the portion 73 of rod 72 and movable therewith, is secured a nozzle member 75 having a depending skirt or flange 115 76 surrounding the guideway portion 66 and in which is a circumferential recess 77. Extending from the under faces of the vane members 48, 49 are arm or lever members 78 which incline downward at an angle of substantially twenty-two and one-half degrees to the horizontal, and the free ends of which seat loosely at substantially opposite points in the recess 77 to form an operative connection between the vanes and said nozzle 75. The nozzle 75 extends upward into aperture 62 with a diametral clearance, preferably of about one-sixteenth of an inch, so as to provide an annular air flow space 78 therearound when the vane members are closed, as shown in full lines in Fig. 4. The nozzle member 75, when the vanes are closed, has its point of discharge substantially in the plane of the top faces of head portions 50, 51, and has in its top end a substantially conical recess 79 which is connected with passageway 74 by a bore or passage 80 coaxial therewith and forming the main fuel jet. The member 75 may also be provided with one or more air bleed ports 81 which open from beneath the vane members into the cup or recess 79 adjacent bore 80. Within the dash-pot chamber 68 is a spring 82, preferably of the coil type, which surrounds rod member 72 and which is held under compression between shoulder 67 and piston 71 to aid the piston 71 in resisting opening movement of vane members 48, 49 and lifting of nozzle 75, and also to return the vanes and nozzle toward lower position. Threaded into the bore 65 in boss 64, is the upper end of hollow guide member 83 having a transverse upper end wall 84 through which is an aperture 15.

85 concentric with piston passageway 74. Adjustably threaded into member 83, as at 86, is a valve stem 87 which depends below member 83 and has a hand grip member 88 for manual adjustment of the stem 87. In the top end of stem 87 is a cylindrical recess 89 in which is seated for lateral and longitudinal play, the flanged end 90 of a tapered metering pin 91 which extends upward loosely through aperture 85 and into passageway 74 for cooperation therewith to determine the size of the main fuel inlet. The pin 91 is secured to the stem 87 by an annular member 92 which overlies the periphery of the flange 90 and which is fixed to the stem—for example, 15 by staking or crimping the stem over onto the member 92. The member 83 is enlarged below the threaded portion 86 to provide an annular packing recess 93 around stem 87, and in which is packing 94. A packing nut or gland 95 threaded into member 83 and surrounding stem 87, 20 serves to maintain packing 94 tightly in position. The gland 95 is preferably provided with a lock nut 96.

The throttle body member 3 seats upon the plate member 54, and at its lower end is substantially rectangular in horizontal section, as at 97, merging above the tops of guide members 56, 57 into a hollow cylindrical portion, as at 98. The members 2 and 3 are rigidly secured together 30 with the plate member 54 clamped therebetween, preferably by means of bolts 99, or the like, passed through flanges 100 projecting from walls 5, 6 and through member 54 and threaded into overlying flanges 101 projecting from member 3. Within the portion 98 is a flow control member 35 or throttle valve 102, preferably of the butterfly type, carried rigidly on a shaft 103 journaled at diametrically opposite points in the wall of portion 98 and having its axis preferably in the vertical plane through the longitudinal center line of passage 11. One end, as 104, of shaft 103 projects through the wall of portion 98 and extends over the reservoir 15. The space within member 3 below valve 102 and above members 48, 49, constitutes a mixing chamber 105, and above the valve 102 is the outlet 106 for the mixing chamber or carburetor, and in which is a series of continuous, parallel, circumferential grooves 107 which aid in homogenizing the mixture passing from the outlet 106.

The foregoing describes the invention so far as it relates to the main fuel and air provisions for forming an explosive mixture in the mixing chamber of the carburetor. I will now describe the invention so far as it relates to certain means for cooperation with the structure above described, in order to provide a proper explosive charge required for proper operation of an engine under certain conditions, for example, starting, warming-up, acceleration, and high power demands, etc.:

Positioned over the space between bracket 16 and wall 6, is a valve casing member 108 having a vertical, substantially cylindrical bore 109 therethrough. The casing 108 is preferably formed integral with the throttle body 3, being secured thereto by conduit members 110, 111. The member 110 (see Fig. 2) extends between the lower end of casing 108 and throttle body portion 98, and has a substantially horizontal bore 112 therethrough which opens at one end into casing bore 109, and at its other end into the mixing chamber 105 anterior of the throttle, and having its longitudinal axis substantially coincident with the line of centers of bore 109 and 75 the mixing chamber. Within the bore 112 is

secured a nozzle member 113 which projects into the mixing chamber 105 and has a horizontal discharge passage 114. The member 111 extends from the front of casing 108 adjacent its lower end to a point behind but substantially in the horizontal plane of throttle shaft 103, and opening from casing bore 109 into member 111 is a passage 115 which communicates with the bore 116 of member 111. The bore 116 is upwardly and rearwardly inclined and opens into the outlet 106 above or posterior of the throttle 102, as at 117. The passage 115 and bore 116 together comprise the upper portion of the carburetor priming or starting passage.

Concentric with bore 109 is a circular aperture 118 (see Fig. 5) through the cover 40, and positioned in said aperture is a sleeve member 119 having at its top a circumferential supporting flange 120 resting upon cover 40. The periphery of flange 120 is notched, as at 121 (see Fig. 1), for cooperation with cover member retaining screw 41^a to prevent rotation of member 119. The member 119 depends into reservoir 15 to a point below the normal fuel level, which is indicated by line L—L. Fitted in the casing bore 109 is the upper end of a hollow, open-ended, cylindrical casing or housing member 122 which projects slightly above casing 108, as at 123, and which extends downward through sleeve member 119 substantially to the bottom wall 4 of the float chamber. The member 122 is held against vertical movement by a set screw 122^a threaded through member 108 and seated at its inner end in a circumferential groove 124 in member 122 to permit free rotation of member 122 in the bore 109, so that the portion of member 122 within bore 109 serves as a rotary valve, as will be presently set forth. Within housing member 122 and slightly below bore 112, is a transverse partition 125 which forms within member 122 the bottom wall of a mixing or fluid chamber 126. Through the wall of chamber 126 and adjacent its upper end, is an air inlet port 127 which normally registers with an air inlet port or passage 128 through the casing 108, and also through said wall 126 is a calibrated port 129 which is normally in register with bore 112 leading to discharge passage 114 (see Fig. 6). Through the wall of chamber 126 is a calibrated port 130 which is slightly larger than port 129 and is arranged to register with passage 112 upon counterclockwise rotation of member 122 sufficient to move passage 127 out of register with air inlet passage 128 and thereby cut off said passage 128. Also through the wall of chamber 126 is a priming port 131 which, upon counterclockwise rotation of member 122 sufficient to carry port 130 out of communication with bore 112, will register with priming passage 115. The top of chamber 126 is sealed by a plunger valve member 132 which upon downward movement covers and cuts off the port 127 and admission of air to chamber 126 through said port. On member 132 which projects above member 122, is a gear rack 133, and fixed by a set screw 134 on the projecting end 104 of the throttle shaft, is a pinion member 135 having gear teeth 136 meshing with said rack, so that rotation of the throttle shaft in moving the throttle toward open and closed positions will reciprocate valve member 132. On the circumference of the member 135 is a lug or projection 137 through which is an internally threaded aperture 138 having its axis transverse to throttle shaft 103, and being, when the throttle valve is closed, substantially horizontal and in the plane of the housing projecting portion 123, as shown in Fig. 5. A 150

part of the periphery of portion 123 is formed with a flat face 139 which, when the housing member 122 is in normal position and throttle valve 102 closed, is in line with aperture 138, 5 the face 139 constituting a cam, for a purpose to be presently described. Adjustably threaded in aperture 138 and projecting therefrom into substantial contact with the flat face 139 when the throttle valve 102 is closed, is a pin 140, so located that upon rotation of housing member 10 122 the face 139 will engage pin 140, and by a cam action therewith rotate throttle shaft 103 to move the throttle valve 102 toward open position. An operating member, preferably in the 15 form of a ring 141, surrounds and is fixed to housing member 122 and rests upon sleeve flange 120, and by means of which, member 122 may be rotated manually. Surrounding member 122 between casing member 108 and ring 141, is a coil 20 spring 142 which is under compression and serves to hold the ring 141 against flange 120. Projecting from the ring 141 are stop arms 143, 144 which cooperate with a stop, preferably one of the cover screws, designated 41^a, to limit rotation of member 122. When arm 143 engages the stop 41^a (Fig. 6), the member 122 is in normal position, and when arm 144 engages said stop (Fig. 8), port 131 is in registry with the priming or starting passage 115, 116. The arm 30 144 also serves as an operating arm for rotation of housing member 122, and is preferably provided with an operating rod or wire (not shown) leading to the dash-board of a car. Depending centrally from and rigid with valve member 132 35 so as to move therewith, is a tubular member 145 having a sliding fit in an aperture 146 in partition 125 and extending downward in member 122 to a point below the normal fuel level in the float chamber. Longitudinally through the member 40 145 is a conduit 147 open at its lower end and communicating at its upper end adjacent member 132 through discharge ports 148 with said chamber 126, and in the wall of member 145 is a calibrated aperture 149 which is normally housed within and closed by partition 125, but which is so positioned as to pass below the bottom 45 face of partition 125 substantially at the time downward travel of the valve member 132 closes air inlet port 127. Also through the wall of member 145 is an air bleed hole 150 which normally opens into chamber 126 but which is so positioned that it starts to move into aperture 50 146 as member 132 cuts off port 127. Through the sleeve member 119 and member 122 within chamber 15, and above the normal fuel level in the float chamber are air inlet ports 151, 152, respectively, which register with each other when rotary housing member 122 is in the normal running position of Figs. 5 and 6, i. e., when port 55 129 is in register with passage 112, but which are of such size in a horizontal plane as to be out of register when port 130 registers with passage 112, as in Figs. 7 and 8. Below port 151 member 119 is of enlarged internal diameter to 60 its bottom end, as at 153, to provide an annular fuel conduit from reservoir 15. Through the wall of rotary member 122 above the normal fuel level, is a fuel-inlet port 154 which opens from the conduit 153 into the interior of member 122. The 65 lower portion of member 122 which extends below the normal fuel level in the float chamber is of enlarged internal diameter to provide a pump chamber 155 having its upper end wall defined by a downward facing annular shoulder 156, and being closed at its lower end by a closure member, 70 75

preferably in the form of a plug 157 threaded into member 122. The lower end of tubular member 145 is of reduced external diameter to provide a downward facing annular shoulder 158 substantially in the plane of shoulder 156 when the throttle valve is closed. Within chamber 155 is a pump piston 159 having a depending circumferential flange 160 and a central aperture 161 into which the reduced end of member 145 extends such that shoulder 158 engages the top face of the piston. Between plug 157 and piston 159 is a coil spring 162 normally urging piston 159 upward against shoulders 156 and 158. Through the plug 157 is a calibrated port 163 coaxial with passage 147. In the top of plug 157 concentric with port 163, is a cylindrical recess providing an annular valve seat 164 with which cooperates a disk member 165 serving as a check valve to prevent flow from chamber 155 to reservoir 15. The member or valve 165 is retained in its recess by a spider or the like 166, preferably secured in position by staking the plug 157 over onto the same, as at 167. The bottom wall 4 80 85 90 95 100 105 110 115 120 125 130 135 140 145 150 155 160 165 170 175 180 185 190 195 200

On the end 104 of throttle shaft 103 beyond pinion 135, is an operating member 171 having a socket therein coaxial with shaft 103 to receive a drive shaft 172 having a radial key or lug 173 which extends into a radial slot 174 in member 171. On the member 171 is an arm 175 which engages a stop lug 176 on the member 3 to limit opening movement of the throttle valve. Also on member 171 is an arm 177 having an adjustment screw 178 which cooperates with casing member 108 to abut the same to limit closing movement of the throttle valve.

The operation of the carburetor of Figs. 1 to 8, inclusive, when the outlet 106 has been connected to the cylinder inlets of an internal combustion engine and reservoir 15 has been connected at inlet 27 to a source of fuel supply, is as follows: The engine being at rest, and it being desired to start the same, the ignition is turned on and the lever 144 is moved manually from its normal running position, Fig. 6, by counter-clockwise rotation to the straining position of Fig. 8 when it will abut the cover-retaining and stop screw 41^a. This movement will rotate housing member 122, causing the cam face 139 to engage pin 140 and rotate the throttle valve 102 toward open position, corresponding to level road car speed of substantially fifteen miles per hour. Rotation of member 122, as just mentioned, closes ports 129, 130 by carrying them out of communication with the nozzle discharge passage 114 and also closes air inlet port 127 by carrying it out of communication with air inlet 128. The said rotation of member 122, however, places priming or starting port 131 in registry with priming passage 115, 116 to place port 117 in outlet 106 above the throttle valve, in direct communication with the fuel reservoir 15 via passage 116, 115, port 131, chamber 126, ports 148, conduit 147, chamber 155, and calibrated port 163. If the engine be now turned over, solid liquid fuel will be drawn from reservoir 15 through port 117 to mix in outlet passage 106 with such air as can pass the throttle valve 102 when the same is in "starting" position. The fuel mixture thus supplied to the engine is exceedingly rich and constitutes a priming or starting charge. If desired, the fuel supplied for start- 150

ing to the outlet 106 from port 117 by suction, may be substantially augmented by rapidly opening and closing the throttle 102, which results in the pump piston 159 forcing solid liquid fuel 5 from the pump chamber 155 up through conduit 147 and port 117 to outlet 106. As the throttle is opened, air entering chamber 10 from inlet 11 at atmospheric pressure will separate the vane members 48, 49 swinging them upward and outward 10 from each other on their shafts 42, 44 toward their full open position, indicated by dotted lines in Fig. 4. The air passing between the vane members 48, 49 is directed by the inclined under faces of the vane members and by the deflector 15 members 58, 59 toward the discharge point from the main fuel nozzle 75. The vane members 48, 49 will be opened proportionally to the difference in pressure between chambers 10 and 105, and the movement of the members 48, 49 acts 20 through lever arms 78 upon nozzle member 75 to simultaneously lift member 75 to maintain the point of discharge therefrom substantially in the plane of least flow area between chambers 10 and 105, i. e., substantially in the plane of the 25 top edges of members 48, 49, so that the fuel in the nozzle member will be maintained in the plane of greatest air velocity and of maximum aspirating effect. The rate of opening and closing of vane members 48, 49 is controlled by the 30 piston 71 and spring 82 in the dash-pot 68 so as to prevent chattering of the vane members at low engine speeds. As the vane members open and close, they raise and lower nozzle 75 and piston 71 with respect to metering pin 91 to control 35 thereby the size of the main fuel inlet to passage 74 and to automatically increase the fuel fed to the main jet 80 and the mixing chamber as the supply of air to the mixing chamber is increased. The tapered metering pin 91 after 40 initial manual adjustment, is held in fixed vertical position during operation of the carburetor. Should it be desired during extremely cold weather conditions, and as soon as the engine is running, to place a load on the engine or drive 45 the car, then as the throttle valve is moved beyond one-third full open position, pinion 135 will act on rack 133 and piston 125 to carry port 149 below partition 125, and since port 151 is out of 50 communication with port 152, additional fuel will be drawn from reservoir 15 through annular passage 153 in sleeve 119, port 154, the bore of member 122 and port 149, into the conduit 147 and thence with the normal priming or starting charge into outlet 106.

55 As the engine warms up, the lever 144, which controls the quality of the mixture, is manually returned to the intermediate position of Fig. 7, which cuts off the priming port 117 from chamber 126 and places port 130 in communication with nozzle discharge passage 114 while air inlet port 127 to chamber 126 is still closed, being out of register with air inlet port 128. When the lever 144 is returned to the position of Fig. 7, cam 139 will permit the throttle valve 102 to return partially toward "idling" position, but not so far as would cause stalling of the engine when the same is cold. In the position of the parts just described, the sub-atmospheric pressure in mixing chamber 105, and the atmospheric pressure maintained over the fuel in reservoir 15 by air inlet port 40^a, will cause liquid fuel to pass from the reservoir 15 through calibrated port 163, conduit 147, ports 148, chamber 126, port 130 and passage 114 into the mixing chamber 105. This 70 liquid fuel from passage 114 is supplemental to that from the main jet 80, and increases the richness of the mixture supplied by the main air and fuel inlets to provide a proper mixture when desired for warming up the engine. As the engine further warms up, the lever 144 is gradually returned manually to normal running position (Fig. 6) when stop lug 143 engages screw 41^a, thus bringing port 129 into communication with the nozzle discharge passage 114 and opening chamber 126 to air inlet 128 through registering port 127. When housing member 122 is gradually rotated by lever 144 from the position of Fig. 7 to that of Fig. 6, then as port 127 begins to admit air to chamber 126, there will be a discharge of air and fuel through passage 114, which continues until port 127 has been rotated far enough to admit sufficient air to chamber 126 to satisfy the mixing chamber suction at port 129. When the engine has been warmed up and housing member 122 returned from the position of Fig. 7 to the position of Figs. 5 and 6, the mixture of air and liquid fuel for normal running will be supplied only from the main air inlet 11 and the main fuel jet 80, but some economizing air will enter the mixing chamber directly through passages 114 80 from chamber 126. When the throttle valve 102 is gradually opened, the registering ports 127, 128 will be gradually cut off by downward movement of plunger valve 132 and will be closed completely at substantially one-third open position of the 85 100 throttle valve corresponding to about sixty miles per hour level road car speed. As the flow area of registering ports 127, 128 is cut down by valve 132, so that air supplied to chamber 126 will no longer satisfy the suction at port 129, then fuel 105 will be drawn from the reservoir 15 through conduit 147 to mix in chamber 126 with some air entering ports 127, 128 and pass therewith through passage 114 to enrich the mixture from the main air and fuel inlets. When ports 127, 128 have 110 been closed completely by valve 132, port 149 will have passed below partition 125 and air passing through ports 151, 152 from the reservoir will enter port 149 and conduit 147 to pass, with fuel drawn up conduit 147 from the reservoir, into 115 chamber 126 as an emulsion, and thence into the mixing chamber 105 through passage 114 to provide a supplemental fuel jet to enrich the mixture from the main air and fuel inlets to supply a proper mixture for maximum power demands. 120 The air inlet port 149 is provided to decrease the effective size of fuel inlet 163 which must be made large in order to permit sufficient flow of priming fuel to port 117. Upon quick opening of the throttle valve 102 from a position corresponding to low 125 130 or normal running speeds, but not to such an extent as to cut off ports 127, 128, a charge of solid liquid fuel will be expelled by pump piston 159 up tube or conduit 147 into chamber 126 and be drawn with air from ports 127, 128 through passage 114 135 into the mixing chamber to supplement the main mixture to provide the desired rich mixture for acceleration. The check valve 165 prevents any back flow through port 163 from chamber 155 into the reservoir 15 and causes all the fuel displaced 140 by piston 159 to pass up conduit 147. The fuel from chamber 126 passes to the mixing chamber 105 through passage 114 and nozzle 113 substantially instantaneously, due to the air at atmospheric pressure supplied from ports 127, 128. 145 After discharge of the displaced fuel from chamber 126, no additional fuel will feed from nozzle 113, but economizing air will again pass therethrough to the mixing chamber. Upon sudden opening of the throttle valve 102 beyond sub- 150

stantially one-third full open position, or sufficiently to cut off ports 127, 128, an accelerating charge of liquid fuel will be expelled from beneath piston 159 up tube 147 into chamber 126, check valve 165 preventing back flow into the reservoir 15. The liquid fuel forced into chamber 126 passes as a solid slug through passage 114 to the mixing chamber, due to the substantially instantaneous closing of port 127 and the fact that pressure of the fuel in conduit 147 prevents entrance of air through port 149. This initial discharge of liquid fuel is followed instantaneously by an emulsion of liquid fuel from the reservoir 15 and air entering conduit 147 through port 149, which emulsion is constant in quantity per unit of time, and which supplies sufficient additional fuel to the mixture from the main inlets to provide maximum power. The air bleed 150 is provided to prevent retention of fuel in chamber 126 should the throttle valve be returned toward closed position just sufficiently to close port 149 without opening ports 127, 128. Since port 150 is above partition 125 as port 149 closes, ports 127, 128 remaining closed, air entering the closing port 149 will pass through conduit 147 and issue from port 150, sweeping any remaining fuel from chamber 126 through the passage 114.

The carburetor illustrated in Figs. 9, 10, 11 and 12 is substantially like that of Figs. 1 to 8 inclusive, but certain details of the structure have been modified slightly. The sleeve member 119 has been omitted and also the fuel inlet 154 to the interior of housing member 122, so that in this carburetor the additional supply of fuel to conduit 147 through port 149 has been eliminated. The air inlet port 152 for supplying air to the air bleed port 149 has been placed above the float chamber and registers in the normal position of housing member 122 with a port 180 in casing 108. The priming passage 116 has been positioned substantially in the vertical plane of and above the nozzle member 113, and therefore opens directly into the bore 109, thus eliminating passage 115. The port 131 while maintaining its relative circumferential position to the other ports in casing 122, has been placed substantially in the plane of air inlet port 127 for movement into and out of registry with passage 116. The ports 129, 130 instead of being in the same horizontal plane have been spaced vertically so that the port 130 cooperates with a separate passage 179 which is above and in the vertical plane of nozzle member 113, and which opens from bore 109 into the mixing chamber 105. The port 129 registers, as in Figs. 1 to 8, in normal position of member 122 with the nozzle bore 114, but the member 113 has a calibrated discharge port 181. In Figs. 10, 11 and 12 are shown certain operative positions of member 122 and of the discharge ports from chamber 126, the detail sectional views in the right-hand column illustrating the positions of the ports for normal running; those in the middle column illustrating the positions of the ports upon partial clockwise rotation of member 122, and being the position for warming up the engine; and those in the left-hand column illustrating the positions of the ports for starting of the engine upon complete clockwise rotation of member 122. The operation of this carburetor, Fig. 9, will be apparent from the foregoing description of operation of the carburetor of Figs. 1 to 8 inclusive.

The following table is given as illustrative of the preferred or allowable range of dimensions in inches of ports which I have found to be satisfactory, but I do not limit myself to such sizes

of ports, as it is evident that other size combinations will also be operative:

		Figs. 1 to 8	Figs. 9 to 12	
Main fuel jet.	80	.085 -.0865	.070	80
Air inlet port.	127	.0937-.125	.0937	
Power port.	129	.070	.0937	
Warming-up port.	130	.0937	.0625-.078	
Priming port.	131	.125	.0937	
Port.	149	.0595	.043	85
Pump inlet.	163	.098	.098	
Air inlet.	162	.1875	.0937	
Main jet bleed.	81	.052		
Fuel inlet.	164	.125		
Air bleed.	150	.040		

What I claim and desire to secure by Letters Patent of the United States is:

1. A carburetor of the character described, comprising a body member having a mixing chamber therein, an air inlet to said chamber, a vane member normally restricting the passage of air from said inlet to said chamber, said vane member being supported for swinging movement to open communication between said inlet and said chamber, a movable fuel nozzle discharging longitudinally into said chamber and having its point of discharge substantially at the free edge of said vane member when said member is in passage restricting position, means interconnecting said vane member and said nozzle to cause substantially simultaneous movement of said nozzle and said vane member whereby the point of discharge from said nozzle is maintained substantially in the plane of maximum air flow velocity, and means fixed in said air inlet to deflect air entering said chamber toward the point of discharge from said nozzle.

2. A carburetor of the character described, comprising a body member having a mixing chamber therein, an air inlet opening into said chamber, oppositely positioned vane members supported adjacent the sides of said chamber for swinging movement, said vane members normally engaging each other at their free edges and being movable into parting relation to control flow of air from said inlet to said chamber, parallel spaced guide members extending between and laterally engaging the side edges of said oppositely positioned vane members, said vane members having an opening therethrough, a reciprocably supported fuel nozzle positioned within said air inlet and terminating in said last-named opening, means to move said nozzle upon swinging movement of said vane members whereby the point of discharge from said nozzle is maintained substantially in the plane of minimum flow area between said inlet and said chamber, and means in said air inlet projecting laterally from said guide members on the inlet side of said vane members to direct air flow toward said nozzle.

3. A carburetor of the character described, comprising a body member having a mixing chamber therein, substantially parallel spaced guide members in said chamber, an air inlet opening into said chamber, vane members positioned between and transversely to said guide members, said vane members being oppositely and swingingly supported at the sides of said inlet and normally engaging each other at their free edges to close communication between said inlet and said chamber, said vane members having an opening therethrough at their free edges, a reciprocable fuel nozzle in said air inlet and terminating in said last-named opening, said nozzle having a discharge port concentric with

said mixing chamber, one of said guide members having means to deflect air toward said nozzle, and means interconnecting said vane members and said nozzle for substantially simultaneous movement thereof whereby the point of discharge from said nozzle will be maintained substantially in the plane of maximum air flow velocity.

4. A carburetor for supplying a mixture of fuel and air to an internal combustion engine, comprising a body member having a mixture passageway, main air and fuel inlets to said passageway, an outlet from said passageway, means to control flow through said passageway, a supplemental fuel supply conduit communicating at one end with a source of fuel supply and at its other end opening into said passageway, an air inlet to said conduit normally operative to supply air to satisfy the passageway suction on said conduit to prevent flow of fuel from said supplemental conduit, a valve operable to regulate said second air inlet whereby the suction in said passageway can draw fuel through said conduit, means actuated with said control means for transmitting movement to and for operating said valve whereby the supply of fuel from said conduit is determined in accordance with the position of said control means, and a second valve controlling said second air inlet and operable independently of said first-named valve whereby to control the supply of fuel from said conduit independently of the position of said control means and in accordance with the needs of the engine.

5. A carburetor of the character described, comprising air inlet member having an air inlet chamber and an air inlet to said chamber, said member having an opening in its wall from said chamber, a throttle body member secured to said air inlet member and having a mixing chamber therein having an open side communicating with said opening, a plate member having an aperture therethrough and being clamped between said members, substantially parallel guide members in said mixing chamber and projecting from said plate member, inclined vane members positioned transversely between said guide members, said vane members being supported by said base member for swinging movement and normally engaging each other at their free edges and having their side edges cooperating with said guide members to restrict flow from said air chamber to said mixing chamber, a tubular guide means positioned in said air chamber and including a dash-pot chamber, a fuel nozzle supported by said guide means for reciprocation and having a piston in said dash-pot chamber, and means on said vane members engaging said nozzle whereby swinging movement of said vane members will move said nozzle.

6. A carburetor of the character described, comprising a body member having a mixing chamber, main air and fuel inlets to said chamber, an outlet from said chamber, means to control said outlet, a casing member having a cylindrical bore, a valve member having a fluid chamber and being rotatable in said bore, means to supply fuel to said fluid chamber, a conduit communicating with said bore and with said mixing chamber, an air inlet to said bore, a plurality of ports in said valve member, certain of said ports registering substantially simultaneously with said second air inlet and with said conduit, another of said ports registering with said conduit when said second air inlet is closed by said valve

member, and a piston valve in said fluid chamber operatively connected to said control means and movable thereby to regulate said second air inlet.

7. A carburetor of the character described comprising a body member having a mixing chamber, main air and fuel inlets to said chamber, an outlet from said chamber, means to control said outlet, a casing member having a cylindrical bore, a valve member having a fluid chamber and being rotatable in said bore, means to supply fuel to said fluid chamber, a conduit communicating with said bore and with said mixing chamber, an air inlet to said bore, a plurality of ports in said valve member, certain of said ports registering substantially simultaneously with said second air inlet and with said conduit, another of said ports registering with said conduit when said second air inlet is closed by said valve member, a piston valve in said fluid chamber operatively connected to said control means and movable thereby to regulate said second air inlet, and means operable by said valve member to regulate said control means.

8. A carburetor of the character described, comprising a body member having a mixing chamber, main air and fuel inlets to said chamber, an outlet from said chamber, a pump chamber having a fuel inlet, a piston in said pump chamber, a casing having a fluid chamber having communication with said mixing chamber, said piston having a piston rod projecting into said fluid chamber, a conduit extending through said piston and rod from said pump chamber to said fluid chamber whereby the fuel compressed beneath said piston will pass through said piston and rod, the wall of said casing having an air inlet port to said fluid chamber normally operable to supply sufficient air to satisfy the mixing chamber suction thereon, and valve means carried by said rod to control said air port.

9. A carburetor of the character described, comprising a body having a mixing chamber, main air and fuel inlets to said chamber, an outlet from said chamber, a throttle valve in said outlet, a fluid chamber, means to supply fuel to said fluid chamber, a conduit leading from said fluid chamber and discharging into said mixing chamber on the inlet side of said throttle valve, a second conduit leading from said fluid chamber and discharging into said outlet beyond said throttle valve, means to control flow through said conduits, an air inlet port to said fluid chamber normally operable to supply air to satisfy the mixing chamber suction thereon, and means operable by said throttle valve to regulate said air port whereby the mixing chamber suction will draw fuel from said fluid chamber into said mixing chamber to supplement the fuel from said main fuel inlet.

10. A carburetor of the character described, comprising a body member having a mixing chamber, main air and fuel inlets to said chamber, an outlet from said chamber, a member having a cylindrical bore, a valve rotatable in said bore and having a fluid chamber, a fuel supply conduit leading from said bore to said mixing chamber, a fuel supply conduit leading from said bore to said outlet, an air inlet conduit to said bore, ports in said valve member registerable with said conduits for placing said conduits in communication with said fluid chamber, and means to supply fuel to said fluid chamber.

11. A carburetor of the character described, comprising a body member having a mixing chamber, main air and fuel inlets to said chamber,

- ber, an outlet from said chamber, a casing member having a cylindrical bore, a valve member rotatable in said bore and having a fluid chamber, a conduit leading from said bore to said mixing chamber, a conduit leading from said bore to said outlet, an air inlet conduit to said bore, ports in said valve member registerable with said conduits for placing said conduits in communication with said fluid chamber, means 10 to supply fuel to said fluid chamber, and means to control the port registering with said air inlet to control thereby the degree of air pressure in said fluid chamber.
12. A carburetor of the character described, comprising a body member having a mixing chamber, main air and fuel inlets to said chamber, an outlet from said chamber, control means for said outlet, a pump chamber, a fluid chamber, a piston in said pump chamber, an 20 operating member for said piston, said operating member having a longitudinal bore opening at one end through said piston into said pump chamber and at its other end having communication with said fluid chamber, a conduit from 25 said fluid chamber to said mixing chamber, a priming passage from said fluid chamber to said outlet, means to supply fuel to said pump chamber, means to normally maintain substantially atmospheric pressure in said fluid chamber, and 30 valve means to control said last-named means, said conduit and said priming passage.
13. A carburetor of the character described, comprising a body member having a mixing chamber, main air and fuel inlets to said chamber, an outlet from said chamber, control means for said outlet, a pump chamber, a fluid chamber, a piston in said pump chamber, an operating member for said piston, said operating member having a longitudinal bore opening at one end through said piston into said pump chamber and at its other end having communication with said fluid chamber, a conduit from said fluid chamber to said mixing chamber, a priming passage from said fluid chamber to said outlet, means to supply fuel to said pump chamber, means to normally maintain substantially atmospheric pressure in said fluid chamber, valve means to control said last-named means, said conduit and said priming passage, and means operable by said control means to cause sub-atmospheric pressure in said fluid chamber.
14. A carburetor comprising a body having a mixing chamber and an outlet, main fuel and air inlets to said mixing chamber, a throttle controlling said outlet, a rotatable hollow valve member, a pump chamber substantially in line with said valve member, a piston in said pump chamber, a reciprocable hollow piston rod carrying said piston and opening at its opposite ends into said hollow valve member and said pump chamber, a port supplying liquid fuel to said pump chamber, passages leading respectively from said hollow valve member to said mixing chamber and to said outlet, said valve member having ports adapted upon rotation of said member to alternately connect said passages with said valve member, means operable by opening movement of the throttle to cause said piston to expel liquid fuel from said pump chamber through said hollow piston rod into said hollow valve member.
15. A carburetor comprising a body having a mixing chamber and an outlet, main fuel and air inlets to said mixing chamber, a throttle controlling said outlet, a rotatable hollow valve member, a pump chamber substantially in line with said valve member, a piston in said pump chamber, a reciprocable hollow piston rod carrying said piston and opening at its opposite ends into said hollow valve member and said pump chamber, a port supplying liquid fuel to said pump chamber, passages leading respectively from said hollow valve member to said mixing chamber and to said outlet, said valve member having ports adapted upon rotation of said member to alternately connect said passages with said valve member, means operable by opening movement of the throttle to cause said piston to expel liquid fuel from said pump chamber through said hollow piston rod into said hollow valve member.
16. A carburetor comprising a body having a mixing chamber and an outlet, main fuel and air inlets to said mixing chamber, a throttle controlling said outlet, a rotatable hollow valve member, a pump chamber substantially in line with said valve member, a piston in said pump chamber, a reciprocable hollow piston rod carrying said piston and opening at its opposite ends into said hollow valve member and said pump chamber, a port supplying liquid fuel to said pump chamber, passages leading respectively from said hollow valve member to said mixing chamber and to said outlet, said valve member having ports adapted upon rotation of said member to alternately connect said passages with said valve member, means operable by opening movement of the throttle to cause said piston to expel liquid fuel from said pump chamber through said hollow piston rod into said hollow valve member, and an air supply port to said hollow valve member controlled by rotation of said valve member.
17. A carburetor comprising a body having a mixing chamber and an outlet, main fuel and air inlets to said mixing chamber, a throttle controlling said outlet, a rotatable hollow valve member, a pump chamber substantially in line with said valve member, a piston in said pump chamber, a reciprocable hollow piston rod carrying said piston and opening at its opposite ends into said hollow valve member and said pump chamber, a port supplying liquid fuel to said pump chamber, passages leading respectively from said hollow valve member to said mixing chamber and to said outlet, said valve member having ports adapted upon rotation of said member to alternately connect said passages with said valve member, means operable by opening movement of the throttle to cause said piston to expel liquid fuel from said pump chamber through said hollow piston rod into said hollow valve member, an admission port to said piston rod opened and closed by movement of the throttle in moving said rod, and ports controlled by rotation of said rotatable hollow member for supplying air to said admission port.
18. A carburetor of the character described, comprising a body member having a mixing chamber, main air and fuel inlets to said chamber, an outlet from said chamber, a casing carried by said member and having a substantially vertical cylindrical bore therethrough, a conduit opening into said bore and communicating with said chamber, a fuel reservoir, a sleeve member rotatably fixed in said bore and depending into said reservoir, a substantially horizontal apertured partition in said sleeve member, a plug member closing the bottom end of said sleeve member and having an aperture therethrough for

- admitting fuel from said reservoir, a piston in said sleeve member and having a piston rod extending upward through said partition aperture, a passage extending through said piston and rod and opening into said sleeve above said partition, an air inlet to said bore, ports in said sleeve member registrable substantially simultaneously with said conduit and said second air inlet, means carried by and movable with said rod and sealing the upper open end of said sleeve member and operable to regulate said second air inlet, and an aperture in said sleeve member registrable with said conduit when said second air inlet is closed.
- 15 19. A carburetor comprising a body having a mixing chamber and an outlet, main air and fuel inlets to said mixing chamber, a conduit for supplying fuel to said fuel inlet, a throttle controlling said outlet, a valve casing having a passage discharging into said chamber on the posterior side of the throttle and a passage discharging into said chamber on the anterior side of the throttle, a valve in said casing having a port cooperable with the first-named passage, said valve having a plurality of ports cooperable with the second-named passage, and means for feeding fuel to said valve for distribution through said ports, said ports being so related to said passages that the first-named passage is closed when the valve is actuated to register either of the second-named ports with said second-named passage, and said second-named passage is closed when the first-named passage is in register with the first-named port.
- 35 20. A carburetor of the character described, comprising a body having a mixing chamber, air and fuel inlets to said chamber, an outlet from said chamber, control means for said outlet, means to supply fuel to said outlet beyond said control means, means to control said second-named means, and means operable by said last-named means to regulate said outlet control means.
- 45 21. A carburetor comprising a body having a mixing chamber and an outlet, main air and fuel inlets to said chamber, a throttle controlling said outlet, a liquid fuel reservoir, a fuel feed duct leading from said reservoir to said outlet beyond the throttle, a valve controlling said feed duct, means for opening and closing said valve, and means on said valve and operable to open the throttle when the valve is moved to open position.
- 55 22. A carburetor comprising a body having a mixing chamber and an outlet, main air and fuel inlets to said chamber, a throttle controlling said outlet, a liquid fuel reservoir, a fuel feed duct leading from said reservoir to said outlet beyond the throttle, a valve controlling said feed duct, means for opening and closing said valve, and a cam mounted on said valve and operable thereby upon opening movement thereof to open the throttle.
- 65 23. A carburetor comprising a body having a mixing chamber and an outlet, main fuel and air inlets to said mixing chamber, a throttle controlling said outlet, a fuel supply reservoir, fuel feed ducts leading respectively from said reservoir to the mixing chamber and to the outlet beyond the throttle, a valve controlling said ducts, means for operating said valve to alternately open and close said ducts, and means operable in unison with said valve to open the throttle when the valve is operated to open the feed duct to the outlet discharging beyond the throttle.
- 75 24. A carburetor comprising a body having a mixing chamber and an outlet, main fuel and air inlets to said mixing chamber, a throttle controlling said outlet, a throttle operating shaft carrying a projection, a liquid fuel reservoir, a fuel feed duct leading from said reservoir to said outlet beyond the throttle, a rotary valve controlling said duct, means for operating said valve, and a cam operable by opening movement of said valve to engage said projection to operate said shaft to open the throttle.
- 80 25. A carburetor comprising a body having a mixing chamber and an outlet, main fuel and air inlets to said mixing chamber, a throttle controlling said outlet, a rotatable hollow valve member, a pump chamber, a piston in said pump chamber, a reciprocable hollow piston rod carrying said piston and opening at its opposite ends into said hollow valve member and said pump chamber, a port supplying liquid fuel to said pump chamber, passages leading respectively from said hollow valve member to said mixing chamber and to said outlet, said valve member having ports adapted upon rotation of said member to alternately connect said passages with said valve member, means operable by opening movement of the throttle to cause said piston to expel liquid fuel from said pump chamber through said hollow piston rod into said hollow valve member, and means controlled by said valve member for admitting air to said valve member when the passage to the mixing chamber is opened by operation of said valve member.
- 90 26. A carburetor comprising a body having a mixing chamber and an outlet, main air and fuel inlets to said mixing chamber, a throttle controlling said outlet, a valve casing having a passage leading to the posterior side of the throttle and a passage leading to the anterior side of the throttle, a valve in said casing having a port cooperable with the first-named passage, said valve having a plurality of ports cooperable with the second-named passage, means for feeding fuel to said valve for distribution through said ports, said ports being so related to said passages that the first-named port is cut off when the valve is actuated to register either of the second-named ports with said second-named passage, and said second-named passage is closed when the first-named passage is in register with the first-named port, and pump means for feeding fuel to certain of said ports.
- 100 27. A carburetor comprising a body having a passage therethrough, a fuel supply conduit discharging into said passage, a throttle controlling flow through said passage, a liquid fuel reservoir, a fuel feed duct leading from said reservoir and discharging into said passage, a valve controlling said feed duct, means to open said valve, a cam operable upon opening movement of said valve, cooperative operating means between said cam and said throttle for moving said throttle toward open position upon operation of said cam, and means for moving said throttle toward open position irrespective of the position of said cam.
- 110 28. A carburetor comprising a body having a passage therethrough, means to supply fuel to said passage, a throttle controlling said passage, a fuel supply reservoir, fuel feed ducts leading from said reservoir to longitudinally spaced points in said passage, valve means controlling said ducts, means for operating said valve means to alternately control said ducts to permit fuel discharge therethrough, cam means operable by said valve means, and cooperative operating means between
- 115 120 125 130 135 140 145 150

- 5 said cam means and said throttle, said cam means acting on said operating means when one of said ducts is dischargeable into said passage to move said throttle toward open position and acting when another of said ducts is dischargeable into said passage to move said throttle further open.
- 10 29. A carburetor of the character described, comprising a body member having a mixing chamber with a mixture outlet, main air and fuel inlets to said chamber, a priming fuel supply conduit opening into said outlet and connected to a source of fuel for discharging priming fuel into said outlet in response to engine suction, a normally closed valve in said conduit, means to control flow from said chamber to said outlet, and means operable by said control means to force fuel through said conduit into said outlet when said valve is open.
- 15 30. A carburetor of the character described, comprising a body member having a mixing chamber with a mixture outlet, main air and fuel inlets to said chamber, a conduit to supply supplemental fuel to said chamber, a normally closed conduit to supply priming fuel to said outlet, valve means to control said first-named conduit and to open and close said second-named conduit, means to supply economizing air to said chamber, means to control flow from said chamber, and means operable by said flow control means to force fuel through one of said conduits and to regulate said air supply means.
- 20 31. A carburetor of the character described, comprising a body member having a mixing chamber, main air and fuel inlets to said chamber, a throttle controlled outlet from said chamber, a pump chamber having a piston therein, means to supply fuel to said pump chamber, a conduit between said chambers, an air inlet port to said conduit normally operable to supply air to satisfy the mixing chamber suction thereon, means to regulate said air port to cause sub-atmospheric pressure in said conduit whereby the mixing chamber suction will draw fuel from said pump chamber, means connecting said last-named means and said piston, and throttle operated means for simultaneously actuating said regulating means and said piston.
- 25 32. A carburetor of the character described, comprising a body member having a mixing chamber, main air and fuel inlets to said chamber, a throttle controlled outlet from said chamber, a member having a cylindrical bore, a valve rotatable in said bore and having a fluid chamber, a conduit leading from said bore to said mixing chamber, a conduit leading from said bore to said outlet, an air inlet conduit to said bore, ports in said valve member registerable with said conduits for placing said conduits in communication with said fluid chamber, and throttle operated means to supply fuel to said fluid chamber.
- 30 33. A carburetor of the character described, comprising a body member having a mixing chamber, main air and fuel inlets to said chamber, a throttle controlled outlet from said chamber, a casing member having a cylindrical bore, a valve member rotatable in said bore and having a fluid chamber, a conduit leading from said bore to said mixing chamber, a conduit leading from said bore to said outlet, an air inlet conduit to said bore, ports in said valve member registerable with said conduits for placing said conduits in communication with said fluid chamber, means to supply fuel to said fluid chamber, means to control the port registering with said air inlet,
- 35 and throttle controlled means to regulate the port registering with said air inlet, said second-named and said third-named means being operable to control the degree of air pressure in said fluid chamber.
- 40 34. A carburetor comprising a body having a mixing chamber and an outlet, main air and fuel inlets to said mixing chamber, a throttle controlling said outlet, a valve casing having a passage leading to the posterior side of the throttle and a passage leading to the anterior side of the throttle, a valve in said casing having a port co-operable with the first-named passage, said valve having a plurality of ports cooperable with the second-named passage, means for feeding fuel to said valve for distribution through said ports, said ports being so related to said passages that the first-named port is cut off when the valve is actuated to register either of the second-named ports with said second-named passage, and said second-named passage is closed when the first-named passage is in register with the first-named port, and throttle operated pump means for feeding fuel to certain of said passages.
- 45 35. A carburetor of the character described, comprising a body member having a passageway therethrough with an air inlet, a vane member normally restricting the passage of air through said passageway, a reciprocably supported fuel nozzle discharging into said passageway, means interconnecting said vane member and said nozzle whereby movement of said vane member will move said nozzle, means operable in response to movement of said nozzle to regulate flow of fuel therethrough, a fuel reservoir connected to said nozzle to supply fuel thereto, a casing member having a dash-pot chamber, said dash-pot chamber receiving liquid fuel from the supply to said nozzle, and a piston in said dash-pot chamber and connected to said nozzle for movement therewith and thereby, the piston in said dash-pot chamber drawing liquid fuel into and discharging liquid fuel from said dash pot chamber upon reciprocation of said nozzle whereby to regulate the movement of said nozzle.
- 50 36. A carburetor of the character described, comprising a body member having a passageway therethrough with an air inlet, a vane member normally restricting the passage of air through said passageway, a reciprocably supported fuel nozzle discharging into said passageway, means interconnecting said vane member and said nozzle whereby movement of said vane member will move said nozzle, means operable in response to movement of said nozzle to regulate flow of fuel therethrough, a fuel reservoir connected to said nozzle to supply fuel thereto, a casing member having a dash-pot chamber, said dash-pot chamber receiving liquid fuel from the supply to said nozzle, a piston in said dash-pot chamber and connected to said nozzle for movement therewith and thereby, the piston in said dash-pot chamber drawing liquid fuel into and discharging liquid fuel from said dash pot chamber upon reciprocation of said nozzle whereby to regulate the movement of said nozzle, and resilient means opposing movement of said vane member toward passageway opening position.
- 55 37. A carburetor of the character described, comprising a body member having a passageway therethrough with an air inlet, a vane member normally restricting the passage of air through said passageway, a reciprocably supported fuel nozzle discharging into said passageway, means interconnecting said vane member and said nozzle

whereby movement of said vane member will move
said nozzle, means operable in response to move-
ment of said nozzle to regulate flow of fuel there-
through, a fuel reservoir connected to said nozzle
5 to supply fuel thereto, a casing member having a
dash-pot chamber, said dash-pot chamber re-
ceiving liquid fuel from the supply to said nozzle,
a piston in said dash-pot chamber and connected
to said nozzle for movement therewith and there-

by, the piston in said dash-pot chamber drawing
liquid fuel into and discharging liquid fuel from
said dash-pot chamber upon reciprocation of
said nozzle whereby to regulate the movement of
said nozzle, and resilient means in said dash-
pot chamber opposing movement of said piston
in response to movement of said vane member
toward passageway opening position.

CERTIFICATE OF CORRECTION.

Patent No. 1,981,483.

November 20, 1934.

WALTER H. WEBER.

It is hereby certified that error appears in the printed specification of the above numbered patent requiring correction as follows: Page 4, line 124, for "straining" read starting; and page 5, line 100, for "passages" read passage; and that the said Letters Patent should be read with these corrections therein that the same may conform to the record of the case in the Patent Office.

Signed and sealed this 27th day of August, A. D. 1935.

(Seal)

Leslie Frazer
Acting Commissioner of Patents.
